UNITED STATES PATENT OFFICE

KARL ALBERT STREUBEL, OF ST. LOUIS, MISSOURI

DESIGN FOR A HAT VENTILATOR

Application filed May 19, 1930. Serial No. 35,693. Term of patent 14 years.

To all whom it may concern:

Be it known that I, KARL ALBERT STREUBEL, a citizen of the United States, residing at city of St. Louis, State of Missouri, have invented a new, original, and ornamental Design for Hat Ventilators, of which the following is a specification, reference being had to the accompanying drawing, forming a part thereof.

Fig. 1 is a front view of a hat ventilator showing my new design as applied to a hat shown in broken lines; and

Fig. 2 is a side view of a hat ventilator.

I claim:

The ornamental design for a hat ventilator, as shown and described.

KARL ALBERT STREUBEL.
